COMBINED WRITING IMPLEMENT AND CUTTER BLADE

Maurice Le Normand, Long Beach, Calif.

Application March 31, 1958, Serial No. 50,239

Term of patent 14 years

(Cl. D74—17)

Fig. 1 is a front perspective view of a combined writing implement and cutter blade showing my new design;

Fig. 2 is a right side elevational view thereof;

Fig. 3 is a front elevational view as it appears with the cutter blade in retracted position;

Fig. 4 is a rear elevational view; and

Fig. 5 is a top plan view thereof.

I claim:

The ornamental design for a combined writing implement and cutter blade, substantially as shown.
